CARPET AND RUG STRETCHER

Harry M. Paternayan, New York, N. Y.

Application June 26, 1934, Serial No. 732,499

6 Claims. (Cl. 254—58)

This invention relates to carpet and rug stretchers and has for an object to provide an improved construction wherein carpets and rugs of any size and shape may be stretched to any desired extent without injury to the carpet or rug.

Another object of the invention is to provide a stretcher which may be mounted in a factory, warehouse or department store and actuated for stretching oriental or other rugs or carpets so that they will assume a desired size and shape.

An additional object, more specifically, is to provide a stretcher which may be connected with any kind of anchoring means and used to stretch either a rug or carpet and under some circumstances to force the rug or carpet against a wall where the rug or carpet is designed to cover the entire floor.

In the accompanying drawings—

Figure 1 is a plan view of a carpet and rug stretcher disclosing an embodiment of the invention, the same being shown in connection with a rug and a specially prepared floor for stretching the rug;

Figure 2 is a sectional view through Figure 1 on the line 2—2, the same being on an enlarged scale;

Figure 3 is an enlarged fragmentary sectional view illustrating a pawl and ratchet embodying certain features of the invention;

Figure 4 is a sectional view through Figure 3 on the line 4—4;

Figure 5 is a sectional view through one of the anchoring plates shown in Figure 1, with a hook or knob shown in connection therewith;

Figure 6 is a sectional view through Figure 5 on the line 6—6;

Figure 7 is a top plan view of the structure shown in Figs. 1 and 2 but with certain parts added thereto whereby the stretcher may be used to force the edge of a carpet against the wall;

Figure 8 is a sectional view through Fig. 7 approximately on the line 8—8.

In laying carpets it is necessary to stretch the same, and quite often it is necessary to stretch the carpet so that one edge will be against each wall of the floor of a room. According to the present invention means have been provided and shown in Figs. 7 and 8 which will accomplish this result in an efficient manner. In the manufacture of rugs, particularly oriental rugs or rugs of this general type, the rug when completed is more or less irregular with curved sides of slightly less area than they should be. Accordingly to cause the rug to assume the desired shape, for

instance, rectangular with straight sides, some stretching of the rug must take place. Various means have been provided heretofore for securing this stretching action but it has been difficult to secure good results except with much labor. In the accompanying drawings, and particularly in Fig. 1 to Fig. 7, an improved structure which will easily and quickly stretch a rug to the desired size and shape without injuring the same, has been provided.

Referring more particularly to Fig. 1 it will be seen that there is provided a floor 1, and on this floor is placed the rug 2 which is secured by tacks 3 and 4 to the floor. It will be noted that the tacks 3 and 4 extend along one end and one side of the rug, leaving the other end and the other side concave and more or less irregular. The stretching device is positioned to stretch the rug longitudinally as illustrated in Fig. 1, and after this stretching operation has taken place the stretching device is moved to the side and the rug is stretched transversely until it lines up with the end and sides at the guiding lines 5 and 6.

As shown in Fig. 1, the numeral 7 indicates what may be called a stretching device, and 8 indicates broadly an anchoring device or harness against which the stretching device 7 reacts when pulling the rug 2. The anchoring device or harness 8 comprises a rectangular bar 9 having chains 10 and 11 at the respective ends. These chains are provided with hooks or interlocking knobs 10' and 11' which interlock with any desired link of the chains 16 and 17, which latter chains are provided with hooks or interlocking knobs 12 and 13 adapted to disengagably interlock with the anchor plates 14 and 15. As shown in Fig. 1 the hooks 10' and 11' are positioned to engage one of the links about midway of the length of the chains 16 and 17 but, if desired, other links could be engaged so as to space the bar 9 nearer or farther from the plates 14 and 15. This arrangement allows for lengthening or shortening the effective length of the chains 16 and 17 to secure the desired adjustment. The interlocking knobs 10' and 11', 12 and 13 are all identical in structure. As shown in Figs. 5 and 6, the plate 18 has a bent down portion 19 with cutaway parts 20 and 21, thus providing overhanging shoulders 22 and 23 which really form a hook or knob interlocking with the plate 15, which plate has a keyhole-shaped aperture so that the hook may be inserted and pulled longitudinally until the parts are as shown in Figs. 1, 5 and 6, whereupon the chain is properly anchored. A U-shaped clevis 24 is slidably mounted on bar 9, said clevis having

a link 25 in which the hook 26 is mounted, said hook being identical to that shown in Figs. 5 and 6. A chain, cable or other flexible connection 27 is provided and connected by a suitable pin 28 to the hook 26. As shown in Fig. 1 the chain or connecting device 27 is formed with legs 27' and 27'', each leg being wrapped around the drum 29. The drum 29 has its ends rotatably mounted in standards 30, which standards are rigidly secured to the upstanding flanges 31, said flanges being part of the angle irons 32 which form a frame when taken with the angle iron 20 and the front plate 34. A seat 35 is mounted at one end of the frame so that the operator may either kneel or sit thereon when operating the levers 36 and 37, and also for acting as means for preventing the free end of the frame from rising when the teeth 38 are pulling. It will be noted that the teeth 38 are connected to a plate 39, and this plate is held in position by suitable screws 40. The teeth 38 may be welded or otherwise rigidly secured to plate 39, and this plate may be secured to the plate or block 39' by screws or other desirable fastening means. The teeth 38 are preferably comparatively long but in order to shorten their effective length one or more auxiliary plates 39'' are slid loosely over the teeth, as shown in Fig. 8, and are merely held thereon by friction. The intention is to have the effective length of the teeth sufficient to puncture and extend almost through the rug without digging into the floor. Also, it will be noticed that there are, in fact, rows of teeth so that the rug will be engaged at a large number of points. As shown in Fig. 2 the chain structure 27 reacts against the link 25 and associated parts and is wound around the drum 29 which is preferably a solid rod. This rod is journaled in the standards 30. A comparatively large gear wheel 41 is rigidly secured to the drum 29 and continually meshes with the pinion 42 which is rigidly secured to shaft 43, also journaled in standards 30.

As shown in Fig. 7, the shaft 43' has a rounded cross section 44 and sections 45 and 46 which are hexagon shaped. This is to permit the levers 36 and 37 to interlock with the shaft to rotate the same when the levers are in their extreme upper position, as illustrated in Fig. 7, to permit the shaft to be free when the levers 36 and 37 are moved to a central point, namely, on the rounded section 44.

The levers 36 and 37 are each provided with a bifurcated portion 47 and in these portions is an aperture 48 through which the hub 49 of a ratchet wheel 50 extends. The ratchet wheel is held against reverse movement by the spring pressed pawl 51, which pawl has a thumb member 52 whereby it may be manually lifted away from the ratchet wheel and turned so that the surface 53 will engage the spring 54, which will thus hold the pawl out of operative position. The ratchet wheel 50 has a bore which is hexagon shaped and of a size to slide over the hexagon shaped sections 45 and 46 of rod 43. By reason of this construction when the levers are in their respective positions as shown in Fig. 7, they may be swung back and forth and in doing so will rotate the shaft 43 in one direction, which in turn will rotate the pinion 42 and this pinion will rotate the gear 41 which is rigidly secured to drum 29, thus causing the drum to wind the respective sections 27' and 27''. This winding action will cause the entire device 7 to move toward the bar 9 and, consequently, will stretch the rug 2. It will be understood that the device 7 may be shift-

ed from time to time along the bar 9, and when shifted the clevis 24 will also be slid along the bar 9. After the rug has been stretched longitudinally to line 5, as shown in Fig. 1, which may be left loose or tacked to the floor, then the device 9 and anchoring structure 8 may be moved around to the side of the rug and the operation repeated for stretching the rug transversely.

As shown particularly in Figs. 7 and 8, the stretching device 7 has been positioned to stretch a piece of carpet 55 so that it will be near or touch the wall, 56. In order to accomplish this result a block 39' is interposed between the plate 39 and the plate 34, whereby the stretching device will be raised in order that the bar 9 may be arranged therebeneath. The chains 10 and 11 are connected with bar 9 in the usual way and with suitable anchoring means of any kind as, for instance, anchoring plates or pinholes provided in the floor. However, other means for anchoring the bar 9 may be used without departing from the spirit of the invention. In this form of the device, when used for this purpose, the chain structure 27 has the sections 27' and 27'' extending over pulleys 57 and 58, which pulleys are mounted on suitable brackets connected to the rear of the frame 59.

It will be noted that the chain sections extend over the pulleys, as just mentioned, and then back to a point near the bar 9, where they are connected to the bar in a similar way to the showing illustrated in Fig. 1. When the parts have been mounted as just described, the levers 36 and 37 are swung back and forth to rotate the drum 29 which will cause the frame 59 to be urged forwardly or towards the wall 56. If the frame 59 and associated parts should tend to rise, the operator may kneel or sit on the seat 35 and hold the same in proper position.

The stretching structure described has been shown stretching a rug and also a carpet. It is to be understood, however, that the device may be used in other ways for stretching rugs or carpets or, in fact, for stretching any articles, and also that the stretching device 7 may be anchored as shown in Fig. 8, or in any other desired manner without departing from the spirit of the invention.

I claim:—

1. A carpet and rug stretcher, including a frame, means carried by the frame for engaging the carpet or rug, an anchoring structure provided with a bar extending transversely of said frame and spaced away from said frame, means arranged at each end of the bar for anchoring the bar, means for connecting the bar with said frame, said means including a clevis slidably mounted on said bar, a flexible structure connected with the clevis, and a drum carried by the frame on which part of the flexible structure is normally wound, and manually actuated means carried by the drum for rotating the drum so as to wind the flexible structure thereon and thereby pull the frame and associated parts towards said bar.

2. A rug and carpet stretcher, including an anchoring structure comprising a bar, a plurality of chains, there being one chain connected to each end of the bar, a hook member carried by each chain, a fixed anchoring eye plate disengageably interlocking with the respective hooks whereby the bar is anchored against movement in one direction, and means connected to the bar for engaging and pulling the carpet or rug towards the bar.

3. A carpet and rug stretcher including an anchoring device and a link, a hook member disengageably interlocking with said link, a flexible structure including a pair of chains connected with said hook structure, a drum secured at the opposite end of said chains, a frame on which said drum is rotatably mounted, a gear wheel rigidly secured to said drum, a pinion continually meshing with said gear wheel, a lever associated with said pinion, a pawl and rack connecting said lever with said pinion, and toothed means extending from said frame for engaging said carpet or rug, whereby when said drum is rotated for winding said chains the frame will be moved toward said anchoring structure and the rug or carpet stretched.

4. A rug or carpet stretcher including an anchoring structure, a frame, a drum rotatably mounted on said frame, a flexible structure whereby when said drum is rotated the flexible structure will be wound to move the frame towards said anchoring structure, a gear wheel rigidly secured to said drum, a pinion continually meshing with said gear wheel, a shaft extending from said pinion and from one side of the frame to the other, said shaft having a pair of polygonal shaped sections and a central round section, a pair of ratchet wheels formed with bores of corresponding shape and size to said polygonal shaped sections whereby the ratchet wheels may be slid onto said sections when the device is functioning and onto the smooth part of the sections when the device is not functioning, a lever for each of said ratchet wheels, and a pawl carried by each of the coacting ratchet wheels

whereby both of said levers may be used to rotate said shaft and said pinion, and means carried by said frame adapted to be interlocked with the carpet or rug for producing a stretching action thereon as said frame moves.

5. A carpet stretcher including an anchoring structure, a frame, means on the frame for engaging the rug or carpet, a pair of chains removably connected to said anchoring structure, a pulley for each chain arranged at the rear of said frame, a single drum arranged at the front of said frame, said chains having one end connected to said drum, and a manually actuated lever mechanism for rotating said drum, whereby as the drum rotates said chains will be wound thereon and said frame will be urged in one direction.

6. A carpet stretcher including a frame, a toothed structure at one end of the frame for engaging a rug or carpet, a supporting traction wheel arranged at the opposite end of said frame, a pair of pulleys arranged at said opposite end of the frame, a chain passing through each of said pulleys, a stationary anchoring structure removably connected with one end of the respective chains, a drum rotatably mounted on said frame connected to the other end of said chains, a gear wheel secured to said drum, a pinion meshing with said gear wheel, pawl and ratchet mechanism coacting with said pinion, and a lever coacting with said pawl and ratchet mechanism for causing the same to function and rotate said pinion.

HARRY M. PATERNAYAN. 35
